UNITED STATES PATENT OFFICE.

ALEXIS F. GILLET, OF OMAHA, NEBRASKA, ASSIGNOR TO JUBILEE MANUFACTURING COMPANY, OF OMAHA, NEBRASKA.

SPARK INTENSIFIER.

Application filed March 23, 1920. Serial No. 363,203.

To all whom it may concern:

Be it known that I, ALEXIS F. GILLET, a citizen of the United States, residing at Omaha, in the county of Douglas and State 5 of Nebraska, have invented certain new and useful Improvements in Spark Intensifiers, of which the following is a specification.

The present invention relates to improvements in spark intensifiers and has for an 10 object to provide an improved device of this character adapted to further indicate on the exterior of the cylinder the condition of the spark therein.

Another object of the present invention 15 resides in providing an indicating spark gap associated with the usual spark plug of an internal combustion engine through which the current must jump in passing to the terminals of the plug and to consequently 20 raise the voltage and insure the production of good sparking within the cylinder.

A further object of the present invention resides in providing an improved spark intensifier that is simple and inexpensive in 25 construction and which is capable of being mounted in conjunction with exciting forms of spark plugs and electrical leads without any alteration or modification in the constructions thereof.

20 The above, and various other objects and advantages of this invention will be in part described in, and in part understood from, the following detailed description of the present preferred embodiment, the same 35 being illustrated in the accompanying drawings wherein:—

Fig. 1 is a side elevational view of a spark plug and a spark intensifier constructed according to the present invention and shown 40 in conjunction with a portion of a cylinder which is illustrated in section.

Fig. 2 is a plan view of a ring insulator.

Fig. 3 is a plan view of a disc insulator.

Fig. 4 is a plan view of a mica disc.

45 Fig. 5 is a top plan view of an assembled intensifier, and

Fig. 6 is a plan view of one of the electrodes.

Referring more particularly to the drawings, 50 10 designates the wall or head of a cylinder forming part of an internal combustion engine, and 11 represents a spark plug of conventional type having the screw threads 12 by which it is removably secured

55 in the cylinder wall or head 10.

The usual form of terminals for the plug 11 are seen at 13 and 14, the customary gap being left therebetween across which the current must jump to form the spark for firing the compressed charge in the cylinder. 60

According to the well known construction the central terminal 14 connects with a rod electrode 15 which projects up through the porcelain top of the spark plug and has an end projecting beyond such top of the 65 plug and which is screw threaded to receive binding nuts 16. The lead or electric wire is connected between the binding nuts 16 according to the present practice for conveying the current down through the central 70 rod electrode 15 to the terminal 14. The current jumping across the gap to the other terminal 13 forms a spark which ignites the vaporized gas in the cylinder. The terminal 13 is grounded through the metal shell 75 on which the threads 12 are formed onto the cylinder 10.

All of the foregoing parts are according to the usual construction. The present invention proposes to introduce between the 80 lead or electric wire 17 and the rod electrode 15 of the spark plug an improved spark intensifier which may be conveniently included between these parts without alteration in the connections. 85

According to the invention the intensifier consists of a pair of electrodes 18 and 19 having perforations 20 and 21 made in their remote ends to receive respectively the upper threaded end of the rod electrode 15 and a 90 binding screw or bolt 22 which is carried by the connector 23 of the wire 17. The electrodes 18 and 19 are made of some suitable metal and are produced preferably after the configuration shown in Figs. 5 and 6. According to this configuration the electrodes have their adjacent ends formed to provide concave recesses 24 arranged opposite one another and having points of horns 25 and 26 located at opposite sides of the recesses 100 24 and providing in effect a double gap across which the spark may jump from the points or horns of one of the electrodes to those of the other. Lateral enlargements 27 and 28 are also embodied in the construction of the electrodes 18 and 19 and such enlargements are provided with perforations 29 and 30 to receive bolts or rivets as hereinafter referred to. 105

A disc or plug 31 of some preferred insu- 110

lating material is secured beneath the electrodes 18 and 19 and holds the same in a predetermined adjusted position with the points or horns 25 and 26 separated a suitable distance. The disc or plug 31 is shown in plan in Fig. 3 and is provided with perforations 32 in alignment with the perforations 29 and 30 made in the electrodes.

Above the electrodes 18 and 19 is placed an insulating ring 33 shown in plan in Fig. 2 and having perforations 34 in alignment with the previously mentioned perforations in the electrodes and disc 31.

A disc 35 of mica or other suitable transparent material is positioned upon the ring 33 with its marginal portions resting thereon. Perforations 36 are made in the mica disc 35 also in vertical alignment with the foregoing perforations.

A suitable binding ring 37 is placed over the mica disc 35. Bolts, rivets, or other fastenings 38 are adapted to pass through various aligning perforations in the disc 31, electrodes 18 and 19, ring 33, mica disc 35 and the binding ring 37 for holding all of these parts together in pre-arranged relation.

In practise, current entering through the wire 17 will pass through the connector 23 screw 22 to the terminal 19 and will jump from the two points or horns thereon to the opposite set of horns of the electrode 18. The current will thence in the usual manner descend through the rod electrode 15 and will jump across the gap formed by the terminals 13 and 14 of the plug. The introduction of a spark gap such as is provided by the terminals 18 and 19 will introduce an increased voltage in the circuit which will be attended with a good spark at the terminals 13 and 14, and will moreover show that the circuit for the particular spark plug is in proper working order, because, should for

any reason the current become short-circuited, it would cease to flow across the gap between the terminals 18 and 19 and observation through the transparent mica disc 35 would immediately show this fact.

It will be appreciated from the foregoing that I have provided a simple and inexpensive device for intensifying the spark in spark plugs and moreover for showing the condition of the spark. The mica disc 35 covers the top of the electrodes and serves to exclude foreign matter from getting thereon while also allowing of the inspection of the spark passing therebetween.

I do not wish to be limited to size, form, or proportion of the various parts. It will be noted that various changes and modifications may be made, provided such changes and modifications are within the spirit of the invention and within the scope of the appended claim.

What is claimed is:—

A spark plug intensifier including a pair of electrodes having recesses formed in their adjacent ends with points at opposite sides of said recesses forming a double spark gap, said electrodes also having lateral enlargements provided with perforations, a disc of insulating material extending in common beneath said electrodes, a ring of insulated material extending in common above said electrodes, a mica disc resting on said ring, a binding ring above said disc, and fastenings passing through said disc, rings, and electrodes for binding the same together in predetermined relation.

In testimony whereof, I have affixed my signature in presence of two witnesses.

ALEXIS F. GILLET.
